UNITED STATES PATENT OFFICE.

LENHART GEORGE SILLER, OF SACRAMENTO, CALIFORNIA.

CLOSURE MOUNTING AND OPERATING MEANS.

Application filed January 28, 1926. Serial No. 84,430.

The invention relates broadly to operating and mounting means for closures which are slidable within frames, and the specific application of the invention herein disclosed, is in connection with sliding sashes of a window. One object of the invention is to provide new and improved means for sliding the closure and applying uniform force to opposite edges thereof during the sliding operation, so that no binding will occur.

Another aim is to so relate certain parts as to permit the closure to be swung laterally from its normal plane whenever desired, and in this connection, a further aim is to provide unique guiding means for the closure when in its normal plane.

A still further object is to provide a simple and inexpensive, yet an efficient and durable, hand-operated unit forming part of the closure-operating means.

With the foregoing in view, the invention resides in the unique subject matter herein-after described and claimed, for carrying out the objects of the invention.

Figure 1 of the accompanying drawings, is a side elevation partly broken away and in section, showing the upper and lower sashes of a window equipped with the invention.

Figure 2 is an edge view partly broken away and in section.

Figure 3 is a horizontal sectional view on an enlarged scale, as indicated by line 3-3 of Fig. 1.

Figure 4 is a detail horizontal section on the planes indicated by lines 4-4 of Figs. 2 and 6.

Figure 5 is an enlarged vertical sectional view as indicated by line 5-5 of Fig. 6.

Figure 6 is a vertical sectional view on line 6-6 of Fig. 3.

Figure 7 is a perspective view showing the relation of gears and racks for sliding the sashes.

Figure 8 is a sectional perspective of a portion of the frame showing the manner in which the gears project into grooves thereof for mesh with the racks of the sashes.

The construction herein disclosed may be considered as the preferred form of the invention, with the understanding however

that within the scope of such invention as claimed, numerous modifications may be made.

F designates a window frame in which upper and lower, slidable sashes U and L are disposed. The mounting and operating means for both sashes is the same and a specific description of such means is only given in connection with the lower sash L. Mounted at the four corners of the frame F are suitable guide pulleys or the like 10. Trained around these pulleys, is a flexible line, preferably comprising two cable portions 11 and a chain portion 12, said cable portions being suitably connected with a hinge member 13 which passes slidably through a vertical slot 14 in a side member 70 of the frame F, said hinge member having an inner leaf 15 suitably secured to the sash L, while the outer end of this member which passes through the slot 14, is preferably provided with a guide 16 engaging the frame. 75 The edge portion of the sash L, contiguous to the hinge member 13, is provided with a longitudinal rib 17 normally received in a longitudinal groove 18 formed in the co-acting side member of the frame, the formation of the rib and groove being preferably that disclosed in Fig. 3. Obviously, when the rib and groove are interengaged, the sash may freely slide, but said rib leaves said groove when the sash is swung inwardly upon the hinge, for instance, to clean the window pane or panes. 85

The chain portion 12 of the flexible line, is disposed at the side of the frame remote from the hinge member 13, said chain portion meshing with the teeth of a sprocket or gear 19. A portion of this sprocket or gear passes through a slot 20 into a groove 21 in the adjacent side member of the frame and meshes with the teeth of a rack bar 22 95 which is retractably connected with the sash L and projects slidably into said groove 21. Means are provided for rotating the member 19 in either direction and it will thus be seen that this member acts upon the rack bar 22 to exert a sliding force on one edge of the sash L, and at the same time, said member drives the flexible line 11-12, so that the latter pulls upon the hinge member 13 at the opposite edge of the sash. Thus, uniform force is exerted at 105

opposite edges of the sash to readily slide the latter and insure that no canting or binding shall take place.

In connecting the rack bar 22 with the sash L, I form said rack bar with upper and lower transverse slots 23 and pass bolts 24 through said slots and the sash, said bolts having thumb nuts 25 which normally clamp the rack bar frictionally against the sash. When these nuts are released however, the bar 22 may be inwardly slid from the groove 21, permitting inward swinging of the sash upon the hinges above described. To facilitate retraction and projection of the bar 22, it is preferably formed with a finger groove 26.

Quite a novel arrangement is provided for mounting and driving the member 19. This member is carried by a short horizontal shaft 30 which is rotatably mounted in a pair of lower lugs 31 projecting from a vertical plate 32 which is secured by screws or the like 33 to the frame F. The plate 32 is also provided with an upper lug 34 and with an intermediate lug 35 between its upper and lower lugs. The lug 34 rotatably supports an operating shaft 36 whose outer end is of suitable form to be engaged by a hand crank (not shown). This shaft is provided with a bevel gear 37 meshing with a bevel pinion 38 on a vertical shaft 39 which is rotatably supported by the upper lug 34 and the intermediate lug 35, the lower end of this shaft 39 being provided with a worm 40 between the lugs 31, which worm meshes with a worm gear 41 carried by the shaft 30. It will thus be seen that rotation of the shaft 36 by means of a hand crank or the like, will drive the shaft 39 and the worm 40, causing the latter and the worm 41 to rotate the shaft 30 and the member 19, for the purpose of adjusting the sash. Moreover, as the worm and worm gear will remain in any position at which they may be stopped, no other locking means are necessary and it will be obvious that the use of sash balances is likewise unnecessary.

Preferably, the lugs 31 are spanned by a short metal strip 42 carrying a guard 43 which prevents accidental disengagement of the chain portion 12 from the member 19, this detail being shown most clearly in Figs. 2 and 4.

It will be seen from the foregoing that simple and inexpensive, yet efficient and reliable means have been provided for carrying out the objects of the invention, and while the details disclosed are preferable, modifications may be made as above set forth.

I claim:—

1. In an operating means for a closure slidable within a frame; cable guides mounted at the four corners of the frame, a flexible line trained around said guides, said line

having a chain portion at one side of said frame, means connecting said line to the closure at the other side of the frame, a sprocket mounted at said one side of the frame and meshing at one side of its axis 70 with said chain portion of the line, a rack bar meshing with said sprocket at the other side of its axis and connected to the closure, and means for driving said sprocket.

2. In an operating and mounting means 75 for a closure slidable within a frame; a gear mounted at the exterior of one side member of the frame and projecting through a slot in said side member to expose its teeth at the interior of the frame, a rack bar re-80 tractably connected to the closure and meshing with said exposed teeth of the gear, and a hinge slidably engaged with a slot in the opposite side member of the frame and directly connected with the closure. 85

3. In an operating and mounting means 90 for a frame-contained closure, a gear mounted at the exterior of one side member of the frame and projecting through a slot in the latter, the inner side of said side member having a longitudinal groove into which the teeth of said gear project, a rack bar projecting edgewise from the closure into said groove and meshing with said teeth of said gear, and means mounting said rack bar on 95 said closure for retraction from said groove.

4. In a closure operating means; a plate 100 for attachment to a frame, an upper lug and a lower pair of laterally spaced lugs projecting from one side of said plate, an intermediate lug projecting from the plate between the upper and lower lugs, a shaft 105 rotatably supported by the upper and intermediate lugs and having a worm between the lower lugs, a closure-operating shaft rotatably supported by the lower lugs and having a worm gear in mesh with said worm, a readily rotatable shaft supported by the upper lug, and gearing connecting said readily rotatable shaft with the first named 110 shaft.

5. In an operating means for a closure 115 slidable and swingable within a frame, cable guides mounted at the four corners of the frame, a flexible line trained around said guides, means connecting said line to one side of the closure, operating means engageable with said line at the opposite side of the closure and retractable means attached to said opposite side of the closure for holding the latter against swinging movement, said retractable means being engageable with said operating means for raising and lowering the closure. 120

6. In an operating means for a closure 125 slidably and swingably mounted within a frame, hinges connected to one side of the closure and having a slidable engagement with the adjacent side of the frame, cable guides mounted at the four corners of the 130

frame, a flexible line trained around said guides and having its ends connected with said hinges, operating means engageable with said line at the sides of the closure opposite to its hinged side, means retractably connected with the closure and engageable with said operating means for raising and lower-

ing the closure, said retractable means being adapted to hold the closure against swinging movement.

In testimony whereof I have hereunto affixed my signature.

LENHART GEORGE SILLER.
